United States Patent Office

Des. 219,698
Patented Jan. 5, 1971

219,698

COMBINED WALLET AND KEY CASE

Nathan Fenster, Brooklyn, and Theodore H. Schiffman, Lawrence, N.Y., assignors to Progress Heat Sealing Co., Inc., New York, N.Y., a corporation of New York

Filed Mar. 2, 1970, Ser. No. 21,685

Term of patent 14 years

Int. Cl. D3—02

U.S. Cl. D87—8.4

FIG. 1 is a front perspective view showing our new design in open position;

FIG. 2 is a front perspective view thereof in a partially closed position;

FIG. 3 is a rear perspective view of FIG. 2; and

FIG. 4 is a rear perspective view thereof in folded position.

We claim:

The ornamental design for a combined wallet and key case, as shown and described.
